MULTICAPSULE SHEET

Charles Nicolle, Gentilly, France

Application October 29, 1945, Serial No. 625,392
In France October 12, 1943Section 1, Public Law 690, August 8, 1946
Patent expires October 12, 1963

5 Claims. (Cl. 206—56)

1

This invention relates to the type of packages designed to contain dosed portions of powdered or granular solid matter or solid matter or compressed or otherwise compacted into pills, pastilles and similar regularly formed bodies or of viscous or liquid matter. The invention is more particularly concerned with assemblies, in sheet form, of a plurality of such packages, in which one of two sheets of thin and pliable packaging material, or both sheets, is, or are formed with a plurality of outwardly bulging portions forming capsule-like containers which are connected by flat portions of the sheets welded, glued or cemented together. The sheet materials generally used for packaging solid or liquid dosed portions of solid or liquid material comprise, amongst others, a variety of plastics including, for instance, cellulose acetate which, like other similar materials, if used, for cost saving purposes, in very thin sheets, possesses very little stiffness and rigidity. If the capsules are large and/or the matter enclosed therein is weighty, as is the case, for instance, with bodies of liquids, the assemblies of greater numbers of such filled packages in sheet-form are liable to crumble or to be torn.

In order to impart to these multi-package sheets the stiffness and rigidity required for properly handling and displaying them, I form the flat portions of the assembly, which extend between the individual capsules, with stiffening or reinforcing ribs formed from the sheet material itself. I prefer to also stiffen and reinforce in the same manner the outer portions of the sheet assembly and quite particularly the border portions, thus forming comparatively rigid frame-like enclosures for the group of capsules assembled in the sheet. I have found that, by preforming one or both sheets, in those flat portions which extend between and around the bulging capsules and are to be welded, glued or cemented together, when the capsules have been filled, with hollow coherent rib-like bulges, the height of these bulges though generally less than the height of the capsule-forming bulges is such as to suffice for preventing the flat portions from limply collapsing or crumbling under the weight of the matter contained in the capsules which, in the case of liquids may be considerable.

These hollow ribs also offer the advantage of facilitating the detaching of individual capsules from the sheet.

In the attached drawing various forms of embodiment of the invention have been shown diagrammatically and merely as examples.

2

In this drawing:

Fig. 1 is a plan view of a first form of embodiment of the invention,

Fig. 2 is a section according to II—II,

5 Fig. 3 is a section of another form of hollow stiffening rib carried out according to the invention.

Fig. 4 is another variant concerning the shape of the ribs.

10 Fig. 5 shows, in plan, a variant of the wrappers shown in Fig. 1 with the line of rib curved and interrupted;

Fig. 6 is a section according to VI—VI of the wrapper carried into effect in Fig. 5

15 Fig. 7 is a plan view of a fragment of another variant of Fig. 1,

Fig. 8 is a section according to VIII—VIII of Fig. 7,

20 Figs. 9 and 10 are sectional views of two forms of ribs carried out in one only of the two sheets of the wrapper, the other not being provided with ribs,

Figure 11 shows, in plan, a wrapper made according to another example of embodiment of 25 the invention, with the application of a variable width rib made in one sheet only,

Figure 12 is a section according to XII—XII of Fig. 11;

30 Fig. 13 is a longitudinal section of another form of carrying out of the invention in which the single rib principle of Figs. 9 and 10 is applied,

Figs. 14 and 15 are sections of other forms of 35 ribs, said ribs being asymmetric,

Fig. 16 is a view of another example of embodiment of the invention in which the ribs are used, at the same time, to introduce decorative elements,

40 Figure 17 is a section according to XVII—XVII of Fig. 16,

45 Figure 18, finally, is a larger scale fragmentary view of a wrapper made according to the invention and showing its effects from the point of view of the separation of the individual units or groups of units.

50 In the form of embodiment shown in Figs. 1 and 2, it is seen that in each of the compartmented sheets 1—1', in addition to compartments 2 and 2' in which the products to be packed are placed ribs 3 and 3' are provided which are intended to give greater rigidity to the plate, as shown in Fig. 1.

55 In the example in Figs. 1 and 2, said ribs are in opposition, that is to say they are turned towards each other,

In the example in Fig. 9, ribs 3 are formed in

one of the sheets only, the second sheet not being provided with ribs. The essential point according to the invention is to have a rib, in at least one of the two sheets, and when there are two ribs, as in the case in Figs. 1 and 2, said two ribs must necessarily be in opposition and never be turned in the same direction since the effect sought for, namely to give rigidity to the whole would not be attained, for when said two ribs are turned in the same direction and nest into one another, due to the slight thickness and pliability of the materials used in the manufacture of the wrapper (cellulose acetate or equivalent plastic materials), such ribs do not constitute a factor of rigidity, but even form the start of a fold in the direction of the rib. In the wrappers one rib invariably meets, as a counterpart in the opposite sheet, either a flat portion to which its edges are attached, or the edges of another opposed rib.

In the example shown in Figs. 1 and 2, ribs 3, 3' are semicircular in section, but it is obvious that they may assume any other suitable shape, they may, for instance, be triangular in shape, as shown at 3a in Fig. 3, or rectangular in shape, in case of need with the corners cut off as shown at 3b in Fig. 4.

Moreover, the lines followed by said ribs may be of any sort whatsoever. They may be either rectilinear as shown in Fig. 1 and intercross for instance at right angles, or follow an outline, regular or not, made up of curves, and in case of need of broken lines as shown in Fig. 5 in which can be seen a rib 4 tacking the exact shape of the plate and associated, in addition, with a rib 5 separating the advertising portion of the plate from the utilisable portion.

As shown in Fig. 6, ribs of different sections can be combined in one and the same wrapper (for instance a rectangular section rib 4 and a semicircular section rib 5), it being moreover possible to adopt any other combination if desired.

The edges of the ribs may, instead of being parallel, as in the examples shown in Figs. 1 to 5, diverge and come closer together so as to produce decorative effects, providing a greater reinforcement of the rigidity at the same time. This has been shown in the example of embodiment in Figs. 7 and 8.

In this form of embodiment, the ribs may be considerably widened at certain portions of the wrapper, in order to surround completely the products to be packed as indicated at 6 in the drawing. Around each compartment 2 there remains a small annular portion 7 by means of which the two sheets forming the wrapper are joined together.

When a wrapper is made with ribs in only one of the two sheets, said ribs are, conformably to the invention, always associated to corresponding flat portions. In this case all sorts of shapes of ribs can likewise be used, both of semicircular section as shown at 3 in Fig. 9, and of rectangular section, as shown at 3c in Fig. 10, or of any other section.

This embodiment with grooves in only one sheet offers a quite sufficient rigidity, for, as soon as the flat portions of the sheets which form the edges of the ribs are fixed by cementing or welding to a part forming a support, they immobilize the edges of said ribs which cannot then move apart, thus, ribs 3 of sheet 1, for instance, can neither open out nor bend, nor collapse, and thus their rigidity is ensured.

In Figs. 11 and 12 an application of the principle of ribs in only one of the two sheets of the wrapper has been shown, in said application the rib itself, as shown at 8, need not necessarily be of absolutely constant width, but should on the contrary be of variable width to enable it to contribute to the effect of ornamentation.

Further, in this Fig. 11, a wider rib 9 has been shown which, at the same time as it contributes to the rigidity of the packing as a whole, permits the introduction inside it of a strip of paper or of any other substance 10, on which are inscribed indications such as: price, name of the product, directions for use, advertising matter.

In Fig. 13 another form of embodiment of the invention has also been shown in which is a lower noncompartmented sheet 1' which is provided with ribs 3' associated with corresponding flat portions of compartmented sheet 1. In said example of embodiment the ribs are positioned beneath the wrapping and are not visible when the upper surface of the wrapper is looked at.

When a rib is made in each of the two sheets of the wrapper, said ribs are not necessarily symmetrical as shown in Figs. 2, 3 and 4, they may be asymmetrical as shown in Figs. 14 and 15.

In the example in Fig. 14, a rectangular section rib 3c and a semi-cylindrical rib 3', which is moreover smaller, have been associated, while in the example, in Fig. 15, upper rib 3d is, for instance, formed by two semi-cylindrical portions, whereas lower rib 3'e is, in section, in the shape of an arc of a circle. Of course, all other shapes of asymmetrical ribs might be used.

When making wrappers constituted by means of sheets of cellulose acetate or equivalent plastic transparent or semi-transparent materials, it is possible to place or to slip into the ribs, as shown at 11 in Figs. 16 and 17 strips or beading made of any material, coloured in case of need, making it possible to obtain certain decorative effects of interest from the advertising point of view and in case of need to further increase the strength of the whole. The compartments shown in Figs. 16 and 17 are spherical in shape, but it is obvious that all other shapes of compartment might be employed according to the products to be packed.

It will thus be seen, from all the foregoing, that the corrugations provided in one of the two sheets or in both the sheets of the wrapper have the effect, in the first place, of giving greater rigidity to the wrapper as a whole and, in addition, to permit of certain decorative effects. But this characteristic of the invention has, in addition, another interesting advantage, in the sense that it makes it possible to effect the separation of the individual units of the wrapper (or of the groups of units), since said ribs constitute natural lines of lesser resistance to tearing, since, all along said ribs, the two opposite thicknesses are spaced a certain distance apart and are not cemented together.

It is easy to understand under these conditions, as shown in Fig. 18, that when a tear is started in one of the ribs, as shown at 12, said tear tends to follow the rib, for, when said tear reaches one edge or the other of the rib, it encounters the two flat portions of the wrapper which are welded together, and therefore far more resistant, the tear is thus checked along the edge of the rib and unavoidably made to follow the latter, as shown at 13 in Fig. 18. It follows either one of the edges of the rib, or goes alternately from one edge to the other.

If desired, in order to further facilitate tearing, and consequently the separation of the units from one another, one of the two ribs, or the flat part associated with the ribs of the other sheet, may be provided with slits or perforations; when ribs are formed in both the sheets, both may even be provided with slits facilitating tearing. It is moreover evident, as previously pointed out, that the section of the rib may be of any sort whatsoever.

It is to be understood that the various wrappers which have been described hereinabove, as examples, and which are all provided with ribs in one at least of the two sheets, said ribs in this case being in opposition to one another, may be provided in their flat portions with all systems of ribs, crosses or not, and with all systems of tearing for the separation of individual units or groups, of units, as well as with all systems for the opening of cells.

Finally, the invention, although applying preferably to wrappers made of cellulose acetate or other equivalent plastic materials, formed by means of precompartmented sheets, might apply in certain of said embodiments of the simpler kinds, to wrappers constituted by means of sheets which would not be provided with compartments beforehand, but between which would merely be placed the products to be packed which are separated from one another by cemented or welded portions of the two sheets.

What I claim is:

1. A multiple package, comprising two sheets of moldable plastic material, at least one of which has a plurality of preformed molded spaced article-receiving recesses separated and surrounded by plane portions, articles in said recesses, said sheets being bonded together substantially throughout said plane portions so that the other sheet covers said recesses, said recesses being arranged in a plurality of rows so that said package has a tendency to bend along lines extending through said plane portions parallel

to the rows, at least one of said sheets having preformed hollow stiffening ribs molded therein and extending transversely across all of said rows, said ribs being effective to resist said bending tendency.

- 5 2. A multiple package as defined in claim 1, in which the recesses in said rows are laterally aligned, and said ribs extend at right angles to one another.
- 10 3. A multiple package as defined in claim 1, in which said stiffening ribs extend around the periphery of said one sheet through its peripheral plane portions.
- 15 4. A multiple package as defined in claim 1, in which said other sheet is provided with complementary preformed hollow stiffening ribs aligned with the ribs of said one sheet.
- 20 5. A multiple package as defined in claim 1, in which at least one of said sheets is transparent, and including a strip of attention-attracting material contained within at least one of said ribs.

CHARLES NICOLLE.
